UNITED STATES PATENT OFFICE.

JULIAN ALGER PEARLL, OF DETROIT, MICHIGAN.

MACHINE FOR MAKING WEATHER-STRIPS.

1,150,145.

Specification of Letters Patent. Patented Aug. 17, 1915.

Application filed November 24, 1914. Serial No. 873,758.

To all whom it may concern:

Be it known that I, JULIAN ALGER PEARLL, a citizen of the United States, residing at Detroit, in the county of Wayne and State 5 of Michigan, have invented certain new and useful Improvements in Machines for Making Weather-Strips, of which the following is a specification.

This invention relates to a sheet metal 10 folder particularly adapted for making or folding weather strips.

In devices heretofore commonly employed for making weather strips, it is necessary to mark the strip of sheet metal where it is to be folded, insert it in the folding means and carefully perceive if the folding mark is in proper place and fold one angle. The strip is then removed, again marked for the further fold and placed in the bending means to 20 complete the second fold, and so on until all the required folds or bends are made. Great care has to be exercised during this old bending operation to prevent the mechanism from over bending the strip or in failing to form right angular bends. This old 25 method of bending results in handling each strip many times, it being necessary to proceed as above noted for at least five times, the fifth or final operation being the formation 30 of the closely folded tongue. By the use of the improved folder or device embodying the features of the invention, the several folds are all completed at one operation of the mechanism or without removing 35 the sheet metal strip from the device until it is completed, it being unnecessary to mark or define the series of fold on the strip as the parts of the device are so coördinated that they will accurately form the 40 several folds in proper positions relatively to each other and at perfect right angles, and when the strip is removed from the folder or device after the bending operation has been completed it will be found absolutely 45 perfect in form according to the pattern desired. Moreover, the improved folder or bending device is simple in its construction, cheap in the cost of manufacture, and consequently can be sold to users at a 50 small cost.

The invention consists in the construction and arrangement of the several parts which

will be more fully hereinafter described and claimed.

In the drawing:—Figure 1 is a perspective view of a folder or bending device embodying the features of the invention and showing the parts in normal position. Fig. 2 is an end elevation thereof, showing the position of the parts in the first folding or 60 bending movements of the same, the bed being partially in section. Fig. 3 is a view similar to Fig. 2 showing the position of the parts when completing the folds or 65 bends. Fig. 4 is a detail perspective view of a weather strip formed by the improved folder or bending device. Fig. 5 shows a modification embodying an improved lock releasing mechanism.

The number 5 designates a bed which may 70 be of any suitable dimensions and material and of block like or practically solid structure having a vertical slot 6 extending full length thereof and through the opposite ends and upper side. In the top portion of the 75 bed a recess or seat 7 is formed and has a closing slide 8 mounted therein with its upper surface flush with the upper surface of the bed, the said slide being of less width than the recess or seat 7. Pins 9 are mounted 80 in the front wall of the recess or seat 7 and loosely extend into the front edge of the slide 8, and surrounding these pins and engaging the front wall of the recess and front edge of the slide are springs 10 which tend 85 to force the slide rearwardly. The rear edge of the slide 8 is formed with an upward and rearward bevel 11 for clearance purposes as will be presently explained. In the slot 6 a vertically movable bending anvil 12 is 90 mounted and has an upper rearwardly and upwardly beveled edge 13, and between the lower edge of the anvil and lower wall of the slot 6 springs 14 and screw bolts 15 are interposed, the springs normally forcing and 95 holding the upper portion of the anvil raised above the top surface of the bed with the rear beveled edge of the slide 8 in contact with the front side thereof. The screw bolts 15 are adapted to guide the anvil in its vertical movement and are fixed to the lower portion of the anvil and slidably project through the bottom of the bed. The screw bolts 15 are also used to adjust the position 100

of the anvil 12 and simultaneously modify the tension of the springs 14. The anvil 12 is held elevated by the springs 14 with considerable resistance to depression but when 5 the resistance of said springs 14 is overcome by pressure imposed on the anvil, the slide 8 will close over the anvil and the slot 6, the beveled edges 11 and 13 coöperating to provide a ready clearance of the anvil by the 10 slide when the anvil has been sufficiently depressed into the slot 6. The opposite ends of the anvil 12 near the upper beveled edge 13 have outward projections or pins 16 by which said anvil is depressed by the operation 15 of the bending wings hereinafter described. The anvil 12 is locked in its depressed position by catch or locking bolts 17 adapted to engage sockets 18 in the anvil, said bolts projecting through the front of 20 the bed and automatically forced rearwardly by springs thereon and engaging collars 20 at their rear extremities. The springs are mounted in bores 21 in the bed and the collars 20 are fixed on the bolts 17 and movable 25 in the bores, the springs 19 being confined between the collars and the front walls of the bores. The outer ends of the catch or locking bolts 17 are provided with pull knobs to release them from engagement with the 30 anvil to restore the several parts to normal position. The anvil is locked down by the bolts 17 to obviate any tendency of upward movement thereof during the bending operation and displacement of the slide 8 while 35 the latter is in its rear slot closing position. In rear of the slot 6 the bed is also formed with a narrow retention slot 22 opening through the top to receive and hold the one edge of the sheet metal plate and to effect 40 the formation of an edge right angular bend.

A preliminary bending wing 23 is mounted on the bed and has its rear edge alined with the rear wall of the slot 22, said wing 45 being connected to the bed by a long hinge 24. A finishing bending wing 25 is hinged at its lower edge to an intermediate portion of the front side of the wing 23 and is of less width than the wing 23 so as to primarily clear the projecting edge of the anvil 12, the hinge 26 of the wing 25 being so disposed as to permit the tongue bend of the weather strip to be produced between the hinged edge of the wing 25 and the lower 50 front portion of the wing 23 when the latter wing is raised to upright position. Each of the wings 23 and 25 has a plurality of handles 27 for operating the same, and the wing 25 has cams 28 fixed to opposite ends 55 to engage the projections or pins 16 on the ends of the anvil. Rising from the rear portion of the bed is an upright 29 and hinged to the upper end thereof is a catch arm 30 with an undercut notch 31 to fit over 60 the upper edge of the wing 23 and hold said 65

wing in fixed upright position to lock the sheet metal strip in its preliminarily bent position while the wing 25 is operated to complete the bends and formation of the weather strip.

In the operation of the device, both wings 23 and 25 are disposed as shown by Fig. 1, and a strip of sheet metal has one side edge first inserted in the retention slot 22, the strip being thereby held vertically close to 70 the edge of the wing 23. The two wings 23 and 25 are then simultaneously raised to vertical position by elevating the wing 23, and the lower edge of the latter wing forces the sheet metal strip over into horizontal 75 position close the upper surface of the bed and simultaneously the strip is also bent vertically against the rear side of the anvil 12, as shown by Fig. 2, thereby shaping the parts 32, 33 and 34 as shown by Fig. 4. The 80 wing 23 is then locked against movement by engaging the notch 31 of the arm 30 with the upper edge thereof as shown by Figs. 2 and 3. The anvil 12 still remains elevated, but as soon as the wing 23 is locked against 85 movement, the wing 25 is turned down and the strip is bent over the beveled edge 13 of the anvil, and the cams 28 engage the projections or pins 16, and, as the said wing is continued in its movement toward a horizontal 90 plane the anvil is gradually depressed until the edge 13 thereof clears the rear beveled edge 11 of the slide 8 and the anvil becomes locked by the bolts 17, when the said 95 slide is forced rearwardly to close over the 100 anvil 12 and slot 6 to form a flat surface against which the part 35 of the strip is formed and at the same time the remaining part 36 of the tongue 37 of the strip is produced, the two parts 34 and 35 of the said 105 tongue being pinched between the lower front portion of the wing 23 and the lower hinged edge of the wing 25. The wing 25 is then thrown up against the wing 23, and the latter is released and both wings are 110 unitedly thrown back on the bed as shown by Fig. 1. The slide 8 instantly resumes its normal position, the bent strip is removed, and the bolts 17 are drawn outwardly to release the anvil 12 which moves upwardly, 115 and all the parts will then be in a position for a repetition of the same operation when another sheet metal strip is placed in vertical position in the slot 22.

In Fig. 5 is shown a construction whereby 120 the locking bolts 17 are simultaneously operated for releasing the vertically movable anvil 12. In said figure, the locking bolts 17 are secured by means of nuts 42 to a laterally movable longitudinally extending bar 125 41, which in turn is connected to the upper ends of vertically disposed members 40 pivoted at 43 to the angle pieces 44 fastened to the bed 5. Extending beneath and transversely to the bed 5 are bars 39 pivoted at 130

45 to the members 40 and at 46 to vertically disposed levers 38 on the opposite side of the bed 5. The levers 38 are pivoted at 47 to angle pieces 48 secured to the bed 5, and the upper extremities of said levers are deflected as at 49. Each of the bending wings 23 and 25 is provided with bails 27' and 27" respectively, which are adapted to engage with the portion 49 of the lever 38. It will thus be seen that when the bail 27' is thrown back upon the bed it is constrained over the deflected extremity of the lever 38, pushing the same forward and exerting a pulling force upon bars 39 and locking the members 40, thus operating to release the locking pins 17 from their sockets and allow the anvil to resume its normal position. This mechanism greatly minimizes manipulation and consequently facilitates the operation of the machine.

It will be seen that a weather strip may be expeditiously, effectively and cheaply produced by means of the improved device by a simple manipulation of the parts which 25 partially act in an automatic manner without marking the blank strip of sheet metal or removing the latter from the device to accomplish the purpose desired.

The improved device is within the pur-
30 chasing scope of any one whether for manu-
facturing or domestic uses, and it is pro-
posed to modify its proportions and dimen-
sions as desired and to use material in its
construction best adapted to render the same
35 strong and durable.

What is claimed is:—

1. In a bending device of the class speci-
fied, a bed having a vertical retention slot,
an anvil depressibly mounted in and nor-
40 mally projecting above the bed and always
maintained in upright position, and a pair
of unitedly movable bending wings mount-
ed on the bed, one wing being movable over
the anvil independently of the other and
45 operating to gradually depress the anvil.

2. In a bending device of the class speci-
fied, a bed having means for holding a sheet
metal strip in bending position, an anvil de-
pressibly mounted in the bed, and always
50 maintained in upright position, and a pair
of bending wings to coöperate with said
means and the anvil, the one wing gradually
depressing the anvil during the bending op-
eration thereof.

55 3. In a bending device of the class speci-
fied, a bed having means for holding a sheet
metal strip in bending position, an anvil de-
pressibly mounted in the bed, and always
maintained in upright position, and a pair
60 of bending wings to coöperate with said
means and the anvil, the anvil being de-
pressed by the movement of the wings and
having one side held parallel with the ad-
jacent side of one of the wings during a por-
65 tion of the bending operation.

4. In a bending device of the class speci-
fied, a bed having means for holding a sheet
metal strip in bending position, a depressible
70 anvil mounted in the bed, a slide auto-
matically operating to close over the anvil
when the latter is depressed, and a pair of
bending wings movably mounted on the
bed, one of the wings being movable over
the anvil onto the slide.

5. In a bending device of the class speci-
fied, a bed having means for holding a sheet
metal strip in bending position, an upright
depressible anvil mounted in the bed, means
75 for automatically locking the anvil de-
pressed, a slide automatically movable in
the bed to close over the anvil, and a pair of
bending wings movably mounted on the bed,
one of the wings being movable over the
anvil onto the slide.

85 6. In a bending device of the class speci-
fied, a bed having means for holding a sheet
metal strip in bending position, a pair of
bending wings movably mounted on the
bed, an upright depressible anvil mounted
90 in the bed, an automatically operating slide
movable over the anvil, and means in part
carried by the anvil and in part by one of
the wings for depressing the anvil at a
proper interval.

95 7. In a bending device of the class speci-
fied, a bed having means for holding a sheet
metal strip in bending position, an upright
depressible anvil mounted in the bed, a pair
100 of bending wings movably mounted on the
bed, one of the wings being movable over
the anvil, and means carried by the anvil
and one of the wings for automatically de-
pressing the anvil.

105 8. In a bending device of the class speci-
fied, a bed having means for holding a sheet
metal strip in bending position, a bending
anvil depressibly mounted in the bed, bend-
ing wings mounted on the bed, the one wing
110 being movable over the anvil independently
of the other, and means for locking one of
the wings in upright position while the re-
maining wing is moved over the anvil.

115 9. In a bending device of the class speci-
fied, a bed having a vertical slot for holding
a sheet metal strip in upright position, a pair
of bending wings movably mounted on the
bed, the one wing having its lower
edge normally coincident with the rear wall
of the said slot, one wing also being of less
width than the other and hinged to the lat-
ter, a depressible anvil mounted in the bed,
the narrower wing being movable over the
anvil, and a slide mounted in the bed to close
over the anvil.

120 125 10. In a bending device of the class speci-
fied, a bed having means for holding a sheet
metal strip in bending position, a depressible
anvil, a pair of bending wings movably
mounted on the bed, the one wing being
hinged to the other and movable over the
130

anvil, and a slide mounted on the bed to automatically close over the anvil, the upper edge of the anvil and the rear edge of the slide being beveled at similar angles to provide for a close bend on the anvil and a ready clearance of the upper edge of the anvil by the slide.

In testimony whereof I affix my signature in presence of two witnesses.

JULIAN ALGER PEARLL.
